UNITED STATES PATENT OFFICE.

MAURICE LACHMAN, OF NEW YORK, N. Y., ASSIGNOR, BY MESNE ASSIGNMENTS, TO BETHLEHEM STEEL COMPANY, OF BETHLEHEM, PENNSYLVANIA, A CORPORATION OF PENNSYLVANIA.

DISK WHEEL.

1,355,233.

Specification of Letters Patent. Patented Oct. 12, 1920.

Application filed November 1, 1918. Serial No. 269,650.

To all whom it may concern:

Be it known that I, MAURICE LACHMAN, a citizen of the United States, and a resident of New York, in the county of New York and State of New York, have invented certain new and useful Improvements in Disk Wheels, of which the following is a specification.

My invention relates to the construction 10 of sheet metal wheels and more particularly to wheels of the disk type.

The object of my invention is to simplify and cheapen the construction of this type of wheel by reducing the number of parts in 15 the complete wheel and to enable the complete wheel with tubular rim or felly and tubular hub to be constructed by simply assembling duplicate struck-up sheet metal disks together back to back.

20 My invention further consists in the novel form of struck-up sheet metal disks adapted for use in making disk wheels.

In my improved wheel each half or duplicate of the wheel comprises essentially a 25 sheet metal disk having two annular grooves one at its periphery and the other at or near its center, said peripheral grooved portions forming, in conjunction with the similarly grooved portions of the companion or duplicate disk, a tubular rim or felly and a tubular hub when said disks are secured firmly together back to back as hereinafter more particularly described and shown.

30 My invention further consists of a sheet metal disk of the form above set forth and having the inner wall of the annular groove at the center extended inwardly as a strengthening flange adapted to engage and be secured to a similar flange on the companion disk.

In the accompanying drawings, Figure 1 45 is a vertical central section of a wheel constructed in accordance with my invention from sheet metal disks formed as above described.

Fig. 2 is a plan of one of said disks from the inner side or face which, in the assembled wheel, is backed against the similar face of the companion disk or duplicate.

50 Referring to the drawings, 1 indicates the body or web part of the struck-up disk having preferably an extensive flat surface or area by which it may engage or seat against a duplicate disk in the completed wheel. 3

indicates a peripheral groove at the edge of 55 the disk the outer wall or flange of which is adapted to meet, by its edge, the similar edge of the duplicate disk to close in the rim and complete the tubular structure of the rim or felly. Said flanges may be welded or otherwise secured together at their edges and if desired, for strengthening purposes, a ring 4 or other reinforcing member may be inserted beneath said flanges and welded or secured to them, although the use of the ring 60 4 is not an essential of my invention in all cases. 65

5 indicates an annular groove or depression at or near the center of the disk, the annular walls 6 of which groove are adapted 70 to meet, at their inner edges, the similar edges of the duplicate disk when the parts are securely fastened together, thereby forming an annular tubular hub. Preferably the inner wall of the hub part is extended or 75 continued inwardly as a flange 7 the flat face of which is adapted to meet and lie against the flat face of the duplicate disk in the completed wheel. The parts may be secured together in any desired manner, as 80 for instance, by bolts running through the tubular hub at the points 8 or by other means. Preferably, the disks or web parts lying flat against one another are spot welded at intervals indicated at 10 and likewise 85 the flanges forming the outer walls of the peripheral grooves may be spot welded at intervals to the interior annular ring lying beneath them. The engaging flanges 7 are 90 rigidly secured together at their meeting faces by rivets or spot welds indicated at 11, thus attaining a very rigid and strong structure. 95

What I claim as my invention is:—

1. A sheet metal wheel having tubular hub and felly, consisting of two struck-up metal disks fastened together back to back, each said disk having an exterior peripheral groove, an interior groove at its hub part, a flat connecting web connecting said grooved parts and an interior flange forming an extension of the side wall of the grooved hub portion and adapted to engage by its inner surface the inner surface of the flange of the duplicate disk. 100

2. A struck-up sheet metal disk adapted for use in the construction of sheet metal wheels and having at both center and rim an 105

- annular groove, the inner wall of the groove at the center being continued into a flange adapted to seat against the similar flange of a duplicate disk to complete the wheel.
- 5 3. A sheet metal wheel having tubular rim and hub and comprising two metal disks arranged back to back, each said disk comprising an exterior peripheral groove, an interior groove at the hub part, a flat web connecting said grooved parts and an interior flange forming an extension of the side wall of the grooved hub portion and adapted to engage by its inner surface the inner surface of the flange of the duplicate disk, said disks being rigidly secured together at the 15 rim and at said interior flanges.
- 10 Signed at New York, in the county of New York and State of New York, this 31st day of October, A. D. 1918.

MAURICE LACHMAN.
